TOOL

Herbert B. Myers and Arsburn Davis, Akron, Ohio,
assignors to Snap-Grip Products, Inc., Akron
Ohio, a corporation

Application October 2, 1940, Serial No. 359,396

10 Claims. (Cl. 29—88.2)

This invention relates to a tool for removing an annular member from a surrounding casing, and more particularly, is concerned with a tool for facilitating the removal of a grease retaining ring, bearing race and/or bearing cone from an automobile axle housing or hub.

Heretofore, the operation of removing a bearing from a front or rear wheel housing or hub on a motor vehicle for repair, grease repacking and the like, has been bothersome and inconvenient because an operator attempts to use standard tools, such as a screw driver bar, hammer and similar tools for the job. Not only has the operation been inconvenient and time-consuming but the operator is liable to damage the parts which are removed unless more than ordinary care and skill is exercised. Further, the operator often loses control of the parts and drops them on the floor or ground where they may pick up dirt.

It is the general object of our invention to avoid and overcome the foregoing and other disadvantages and difficulties of prior art practices by the provision of a relatively inexpensive and long-wearing tool which can be quickly operated by the ordinary workman to remove without damage and without falling an annular member from a surrounding housing.

Another object of our invention is to provide an expanding gripper tool which can be instantly engaged in diametrically balanced relation with the inside of a bearing race, cone, grease retainer or similar member, and which can then be struck with a hammer to move the tool longitudinally in either direction to push or to pull the engaged object out of a surrounding member.

Another object of our invention is the provision of a mechanism for removing bearings and the like and including a pair of drop-forged gripping members resiliently held in spaced apart, opposed, and oppositely facing position and having a bearing-receiving or ring-receiving groove therein, and having pushing shoulders and pulling shoulders thereon.

Another object of our invention is to provide a tool of the type described wherein a drop-forged handle is provided with outwardly diverging flat spring arms at one end, each arm having a drop-forged gripping member secured to its outer end.

The foregoing and other objects of our invention are achieved by the provision of a tool including a handle, means on the handle whereby it can be driven with a hammer in either direction along its axis, a pair of flat spring fingers

extending outwardly from one end of the handle and forming an angle of less than about thirty degrees with each other, a gripping member secured to the outside of the end of each spring finger, said gripping members together having a substantially round shape in cross section when the spring fingers are pressed together. The gripping members are usually formed with tapered outer ends, and two pushing and one 10 pushing shoulders on each member, the pushing shoulder and one pulling shoulder being opposed to each other and defining a relatively wide groove between them.

For a better understanding of our invention, reference should be had to the accompanying drawing wherein Fig. 1 is a side elevation of an embodiment of our invention and incorporating the principles thereof; Fig. 2 is a plan view of the tool shown in Fig. 1; Fig. 3 is a cross-sectional view taken on line III—III of Fig. 2; and Fig. 4 is a longitudinal sectional view through a wheel hub and on reduced scale and illustrating one manner of using the tool.

In the drawing the numeral 10 indicates, as 25 a whole, a handle usually made of drop-forged or other strong and long-wearing steel, and including an integral laterally-offset shoulder 12 positioned at one end of the handle. The end of the handle 10 remote from the shoulder 12 is appropriately recessed on opposite sides to receive the ends of flat spring fingers 14 which are conveniently made from hot-rolled, flat steel wire, full hard-tempered and thereafter stamped to the shape and formed with the slightly bent ends as shown. The ends of the spring fingers 14 may be secured to the handle 10 in any suitable manner, but preferably by rivets 16. The spring fingers 14 extend outwardly from the handle 10 at a diverging angle, usually less than thirty degrees and most generally at an angle of between about seven and about twenty degrees, and ordinarily about fifteen degrees.

The ends 18 of the spring fingers 14 remote from the handle 10 are bent slightly so that they 45 are substantially parallel to each other. A gripping member, indicated as a whole by the numeral 20, is mounted on the outside of the end 18 of each spring finger 14 so that the gripping members 20 together form a pair of opposed but outwardly facing gripping means. Preferably, each gripping member is recessed to receive the end 18 of the spring finger 14 and the parts are secured together in any suitable way but preferably by rivets 22, as shown.

The gripping members 20 are preferably drop-

forged steel, but, of course, can be made from any strong long-wearing steel. Each member 20 is substantially half round in cross-section, as best seen in Fig. 3, so that when the spring fingers 14 are pressed together the gripping members 20 together form a substantially round assembly which facilitates threading or moving them inside an annular member to be engaged. For like reasons, the outer ends of the gripping members are curve-tapered, as at 24, and the inner ends are formed with a tapered boss 26 which not only strengthens the assembly but acts to facilitate engagement and disengagement of the gripping members with the annular member engaged.

Each gripping member 20 is formed with a groove 30 on its outer surface and the groove is sufficiently wide and deep to receive and hold a bearing ring, race, grease retainer, or other annular member of up to a desired size. The groove 30 provides a pushing shoulder 32 and a pulling shoulder 34 usually of somewhat less height. A pulling shoulder 36 of greater height and strength and substantially equal to the shoulder 32 is provided adjacent the boss 26, as clearly shown in Fig. 2 of the drawing.

In the operation of the tool to remove, for example, a bearing race 40 from a hub 42 of a wheel (see Fig. 4), the operator squeezes the spring fingers 14 together and threads or inserts the gripping members inside the race until either the shoulders 34 or the shoulders 36 are behind the race. Thereupon, the spring fingers 14 are released and the gripping members move out into engagement with the race as shown in Fig. 4. In this figure, the shoulders 34 are shown as engaging the race 40 although it should be understood that these shoulders are only for a light pull. If a heavy pull is required the heavier shoulders 36 are engaged with the annular member.

Now, the shoulder 12 of the tool is struck with a hammer in the direction of the arrow in Fig. 4 to slide the race 40 out of the hub 42. It will be recognized that the race 40 is gripped tightly by the tool which presents the race from dropping on the floor. Also, the force applied by the tool to the race is at diametrically balanced points which can be readily changed circumferentially so that the race or other annular member is not damaged.

In a similar manner, our improved tool can be used to push an annular member from a surrounding housing and in this case the operation is the same as before except that the end of the handle 10 adjacent the shoulder 12 is struck with a hammer in a direction opposite to the arrow shown in Fig. 4. The shoulders 32 during the pushing operation engage with the annular member to be removed and as before the annular member is held by the tool after removal.

From the foregoing, it will be seen that the objects of our invention have been achieved by the provision of a strong, relatively-inexpensive, and easily operated tool which can be quickly operated to remove with either a push or a pull substantially any annular or shouldered member from a surrounding casing or housing. Our tool can be made in any of a plurality of sizes to best handle a given set of operations, but is conveniently made about fourteen inches long and so that it will engage bearings or the like from between about one and one-quarter inches to about two and one-half inches in inside diameter and up to about one and one-half inches in length. A tool of this size will handle substan-

tially all passenger automobile bearings and light and medium trucks.

With our improved tool the removal and repacking or repair of motor vehicle and other bearings from surrounding housings is greatly facilitated. Damage to parts is substantially eliminated, time is greatly reduced, and labor costs are materially pared.

Although in accordance with the patent statutes, we have illustrated and described one embodiment of our invention in detail, it will be understood that we are not to be limited thereto or thereby, but that the scope of our invention is defined in the appended claims.

15 We claim:

1. A tool for removing an annular member from a surrounding housing and comprising a drop-forged handle, an integral, laterally-offset shoulder adjacent one end of the handle, a pair of spring steel fingers secured in opposed relation on opposite sides of the other end of the handle and diverging outwardly at a relatively small angle to the axis of the handle, a pair of drop-forged, gripping members, one of which is secured to the outside of the end of each spring finger so that they are in substantially parallel relation to each other, each gripping member having a pair of longitudinally-spaced outwardly-directed shoulders, tapered ends and substantially a half-round shape in cross section, and with the flat side of each member lying against its associated spring finger, and rivets securing the spring fingers to the gripping members and to the handle, said spring fingers being received in complementary recesses in the handle and gripping members.

2. A tool for removing an annular member from a surrounding housing and comprising a drop-forged handle, an integral, laterally-offset shoulder on the handle, a pair of spring steel fingers secured in opposed relation on opposite sides of one end of the handle and diverging outwardly at a relatively small angle to the axis of the handle, a pair of drop-forged, gripping members, one of which is secured to the outside of the end of each spring finger, each gripping member having a pair of longitudinally-spaced outwardly-directed shoulders, a tapered outer end and substantially a half-round shape in cross section with the flat side of each member lying against its associated spring finger, and means securing each spring finger to a gripping member and to the handle, said spring fingers being received in complementary recesses in the handle and gripping members.

3. A tool for removing an annular member from a surrounding housing and comprising a steel handle, and integral, laterally-offset shoulder on the handle, a pair of spring steel fingers secured in opposed relation on opposite sides of one end of the handle and diverging outwardly at a relatively small angle to the axis of the handle, and a pair of steel gripping members, one of which is secured to the outside of the end of each spring finger, each gripping member having an outwardly-directed shoulder, a tapered outer end and substantially a half-round shape in cross section with the flat side of each member lying against its associated spring finger.

4. In combination in a tool, a handle, means on the handle whereby the handle can be driven with a hammer in either direction along its axis, a pair of flat spring fingers extending outwardly from one end of the handle and forming an angle of less than about thirty degrees with each other,

a gripping member secured to the outside of the end of each spring finger, said gripping members together having a substantially round shape in cross section when the spring fingers are pressed together and having tapered outer ends, and two pulling and one pushing shoulders formed on each gripping member, the pushing and one pulling shoulder being opposed to each other and defining a relatively wide groove between them.

5. In combination in a tool, a handle, a pair of flat spring fingers extending outwardly from one end of the handle and forming an angle of less than about thirty degrees with each other, a gripping means associated with the outside of the end of each spring finger, said gripping means together having a substantially round shape in cross section when the spring fingers are pressed together and having tapered outer ends, and two pulling and one pushing shoulders formed on each gripping means, the pushing and one pulling shoulder being opposed to each other and defining a relatively wide groove between them.

6. In combination in a tool, a handle, a pair of flat spring fingers extending outwardly from one end of the handle and forming an angle of less than about thirty degrees with each other, a gripping means associated with the outside of the end of each spring finger, two pulling and one pushing shoulders formed on each gripping means, the pushing and one pulling shoulder being opposed to each other and defining a relatively wide groove between them.

7. In combination in a tool, a handle, a pair of flat spring fingers extending outwardly from one end of the handle and forming an angle of less than about thirty degrees with each other, a gripping means associated with the outside of the end of each spring finger, and a pulling and a pushing shoulder formed on each gripping means, the pushing and the pulling shoulder being op-

posed to each other and defining a relatively wide groove between them.

8. A tool including a cooperating pair of gripping members adapted to be moved away from each other and into engagement with the inner periphery of an annular ring or similar work, and supporting means resiliently positioning the gripping members in spaced apart relation, but permitting the gripping members to be moved together, each gripping member having at least one end tapered and a relatively wide groove formed near its middle portion and defining a pair of opposed work-contacting shoulders, and another work contacting shoulder formed on each gripping member.

9. A tool including a cooperating pair of gripping members adapted to be moved away from each other and into engagement with the inner periphery of an annular ring or similar work, and supporting means resiliently positioning the gripping members in spaced-apart relation but permitting the gripping members to be moved together, each gripping member having at least one end tapered and a relatively wide groove formed near its middle portion and defining a pair of opposed work-contacting shoulders.

10. A tool including a plurality of gripping means adapted to be moved away from each other and into engagement with the inner periphery of an annular ring or similar work, and supporting means associated with and resiliently positioning the gripping means in spaced-apart relation but permitting the gripping members to be moved together, each gripping means having a relatively wide groove formed near its middle portion and defining a pair of opposed work-contacting shoulders.
